United States Patent

Des. 237,594
Patented Nov. 11, 1975

237,594

AIRCRAFT FLIGHT INSTRUMENT

Lee J. Vetter, Overland Park, Kans., assignor to King
Radio Corporation, Olathe, Kans.

Filed July 12, 1973, Ser. No. 378,706

Term of patent 14 years

Int. Cl. D10—04

U.S. Cl. D10—67

Fig. 1.

Fig. 2.

FIG. 1 is a front elevational view of an aircraft flight instrument showing my new design with flags obscuring certain scales to indicate an off condition;

FIG. 2 is a front elevational view thereof with the obscuring flags removed.

The sides and rear of the claimed design, not shown, are plain and unornamented.

I claim:

An ornamental design for an aircraft flight instrument, as shown and described.
